FOLDABLE TRAP RAKE

Ralf Francis Mervyn Roughsedge, 1 Nancy St., St. Marys, near Sydney, New South Wales, Australia

Filed Sept. 25, 1970, Ser. No. 25,198

Claims priority, application Australia Apr. 20, 1970

Term of patent 14 years

Int. Cl. D8—01

U.S. Cl. D8—13

FIG. 1.

FIG. 4.

FIG. 2.

FIG. 3.

FIG. 1 is a top plan view of my new foldable trap rake; showing my new design;

FIG. 2 is a front elevational view of said trap rake;

FIG. 3 is a side elevational view of said trap rake; and

FIG. 4 is an isometric view taken from above and to one other side of said trap rake when it is in the folded position.

I claim:

The ornamental design for a foldable trap rake, as shown.
